UNITED STATES PATENT OFFICE.

FREDERICK HAGER, OF PORTLAND, OREGON.

BOOK-BACKING.

SPECIFICATION forming part of Letters Patent No. 651,351, dated June 12, 1900.

Application filed June 22, 1899. Serial No. 721,427. (No model.)

To all whom it may concern:

Be it known that I, FREDERICK HAGER, a citizen of the United States, and a resident of Portland, county of Multnomah, and State of Oregon, have invented certain new and useful Improvements in Book-Backings, of which the following is a specification, reference being had to the accompanying drawings, forming a part thereof, in which similar letters of reference indicate corresponding parts.

This invention relates to improvements in backs of the classes employed in the art of book-binding for backing and assembling the several signatures comprising a book-body.

The invention embodies a strip-sheet and a flexible base; and the object thereof is to provide an efficient article of this character in which the strips comprising the strip-sheet are of a construction adapted to be secured to the flexible base in perfect parallel alignment.

The invention will be hereinafter fully described, and specifically set forth in the annexed claims.

In the accompanying drawings, forming part of this specification, Figure 1 is a face or plan view of a back embodying my improvements. Fig. 2 is a detail transverse sectional view taken on the line 2 2, Fig. 1; and Figs. 3 and 4 are perspective views illustrating the relative arrangement of the back with a book-body.

Heretofore in the bookbinder's art these backs have been formed by pasting separate strips of cardboard upon a flexible base or fabric, said strips being arranged in pairs with their adjoining edges abutting and the respective pairs being parallel and separated by a narrow intervening space; but this method of pasting the separate strips upon the flexible base or fabric is exceedingly tedious and slow, and a perfect parallel alignment of the pairs of strips is virtually impossible. The variation in the width of the

separating-spaces between the respective pairs of strips makes the back irregular and precludes its perfect operation when applied in position in the binding of the book. It is the purpose of my present invention to entirely obviate the above disadvantages and to produce a back in which the strips will be

in perfect and accurate alignment, so that the maximum degree of efficiency and operation is secured and the time necessary in an effort to align the severed strips is saved. 55

Referring to the drawings, A designates the flexible base or sheet, which may be of fabric or any other suitable or desired material.

B designates the strips of cardboard or analogous material which are pasted upon the flexible base. These strips are produced by approved machinery in a series of pairs b, having their meeting edges abutting, said pairs being in perfectly-parallel relative position and separated by the narrow intervening space b'; but the strips of the respective pairs are connected by narrow integral necks n, extending across the intervening space b'. In practice the series of strips, as just above 70 described, are provided upon their backs with mucilage or other suitable adhesive substance by which they may be pasted upon the flexible base A, and it will be understood that the narrow integral connecting-necks n 75 will retain the strips in permanent connection and parallel alignment until they are secured to the flexible base, thus avoiding all guesswork, loss of time, or the use of the eye in securing a parallel alignment of the strips. 80

Another important feature of my improvements is that the adhesive substance is applied to and carried upon the back of the connecting-strips, so that only that part of the flexible base which is covered by the strips 85 receives any of the adhesive substance, while in the practice heretofore pursued in the art in the operation of pasting single strips one by one upon the flexible base the adhesive substance was first applied to the whole surface of the flexible base and the strips were set upon said adhesive surface, which operation was not only uncleanly, but the adhesive substance also caused the flexible base 90 to shrink and become stiff and hard. 95

The operation and advantages of my invention will be readily understood by those skilled in the art to which it appertains.

The several signatures, as C, comprising the book-body are respectively sewed to the flexible base A by means of threads c, which pass through the said base into the space b'. The

strips are then folded upon each other to bring the several signatures together and form the book-body C', as illustrated by Fig. 4 of the drawings. The integral narrow connecting-necks n will not interfere to any degree whatever with the flexibility secured by the intervening spaces b' when my improved backing is applied in position, and after the strips are secured upon the flexible base 10 and the backing is in position the dividing-cut line, as shown at l, between the respective strips of each pair, which forms the abutting edges of said strips, will open up freely, while the exact uniform size of the spaces b' 15 will insure a true and perfect operation.

I do not confine myself to the specific details of mechanical construction as herein shown and described, as it is obvious that under the scope of my invention I am entitled 20 to structural variations.

Having thus described my invention, what I claim as new, and desire to secure by Letters Patent, is—

1. As an improved article of manufacture, a strip-sheet for backing and assembling book-signatures, embodying a pair of strips in parallel position with a uniform intervening space bridged by integral narrow connecting-necks extending between said strips, substantially as shown and described. 25

2. As an improved article of manufacture, a strip-sheet for backing and assembling book-signatures, embodying pairs of strips with their meeting edges abutting and retained together, said respective pairs being in parallel position and separated by a uniform intervening space bridged by an integral narrow connecting-neck extending between the strips 30

of the respective pairs, substantially as and for the purpose set forth. 40

3. As an improved article of manufacture, a strip-sheet for backing and assembling book-signatures, embodying pairs of strips in parallel position and separated by a uniform intervening space bridged by integral narrow connecting-necks, said strip-sheet being provided with and carrying upon its back an adhesive substance, whereby it may be applied to a flexible base, substantially as and for the purpose set forth. 45

4. As an improvement in backs for assembling book-signatures, the combination, with a flexible base or fabric, of a strip-sheet embodying pairs of strips in parallel position separated by uniform intervening spaces bridged by integral narrow connecting-necks, and means for attaching said strip-sheet to the flexible base, substantially as and for the purpose set forth. 50

5. As an improved back for assembling book-signatures, the combination, with a flexible base or fabric, of a strip-sheet embodying pairs of strips in parallel position separated by uniform intervening spaces bridged by integral narrow connecting-necks, and an adhesive agent attaching said strip-sheet to the flexible base, substantially as shown and described. 60

In testimony that I claim the foregoing as my invention I have signed my name, in presence of two witnesses, this 13th day of June, 1899. 70

FREDERICK HAGER.
